UNITED STATES PATENT OFFICE.

NORMAN ELLIOTT, OF CLEVELAND, OHIO.

LAMP FOR VEHICLES.

1,389,037.

Specification of Letters Patent. Patented Aug. 30, 1921.

Application filed April 28, 1921. Serial No. 465,262.

To all whom it may concern:

Be it known that I, NORMAN ELLIOTT, a citizen of the United States, residing at Cleveland, in the county of Cuyahoga and 5 State of Ohio, have invented a certain new and useful Improvement in Lamps for Vehicles, of which the following is a full, clear, and exact description, reference being had to the accompanying drawings.

10 This invention relates to lamps for vehicles (such as automobiles) and has for its general object to provide a lamp which will be capable of operating efficiently not only as a tail lamp, but as a warning lamp to indicate to others the stopping of the vehicle or 15 the checking of the speed thereof, as by the application of the brakes thereto. A further and more limited object of the invention is to improve and simplify the construction 20 and operation of lamps of this character.

I accomplish these objects in and through a lamp such as shown in the accompanying drawing, wherein Figure 1 represents a rear elevation thereof and Fig. 2 a central vertical sectional view corresponding substantially to the line 2—2 of Fig. 2, both bulbs and their sockets being shown in elevation.

Describing the parts by reference characters, 1 denotes a sheet metal casing, generally 30 hemispherical in shape and having its open end provided with an angular peripheral flange 2 forming a seat for the lens or pane 3. The said lens or pane is preferably plain as to its upper section, and has formed there- 35 with a convex lens portion 4 in its lower section.

The upper portion of the pane has molded thereon or otherwise applied thereto a warning signal, shown as the word "Stop" the 40 letters of which are of a color which, when the upper section of the pane is illuminated, will contrast with the color of the said upper section. For this purpose the glass of the upper section may be clear or dark and the 45 glass corresponding to the letters may be red.

The pane 3 may be secured upon its seat within the flange 2 by means of a split channel-shaped locking ring 5 having lugs 6 connected by a bolt or screw 7.

The casing 1 is divided by a central horizontal partition 8 extending from the rear or open end thereof to the closed or front end. Mounted in and projecting upwardly

from said partition is a socket 9 for the neck 55 of a bulb 10. Also mounted in and projecting downwardly from said partition is a socket 11 for the neck of a bulb 12. Within the upper compartment provided by the casing 1 and the partition 8 there is located a 60 reflector 13, said reflector coöperating with the bulb 10 to assist in illuminating the warning signal on the pane 3.

The lower portion of the pane is shown as 65 provided with a convex lens section 4, in order to provide with the bulb 12 an efficient tail light. Where such convex lens is employed, the portion of the pane below the partition 8 and surrounding the said lens may be opaque.

Below the bulb 12, the casing is provided with a slot 14 which is covered by a pane of suitable transparent material, such as mica, indicated at 15.

The bulb 10 is intended to operate automatically (and preferably by the application of the service brakes) to illuminate the warning or "stop" signal as the movement of the vehicle is checked. Any of the standard or known methods of controlling the circuit including said bulb may be employed for this purpose. The bulb 12 is intended to be operated in the usual manner for tail-light purposes, the lamp being placed above and in front of the license plate so that the 85 white light projects through the slot 14 and pane 15 may illuminate said plate.

The front or closed end of the casing 1 is flattened, as indicated at 16, providing a convenient means for attachment of the lamp to 90 a bracket 16.

By reason of the construction and arrangement of parts shown and described herein, I have produced a lamp which is capable of operating in a most satisfactory 95 manner for the double purpose of automatically illuminating or displaying a warning signal as well as operating as an efficient tail lamp. Furthermore, I have accomplished this result in and through a construction and arrangement of parts which result in simplicity of construction and economy of production.

By making the lens 4 a unitary part of the pane 3, a single clamping device suffices 105 for the cover for both the warning signal compartment and the tail light compartment of the lamp. The partition 8 preferably

abuts against the pane 3, thereby bracing the pane and lens construction and minimizing the danger of breakage.

Having thus described my invention, what 5 I claim is:

A lamp comprising a casing having an open round end, a partition extending from the closed end of the casing to the open end thereof and dividing the same into a pair of 10 compartments, a pane covering the open end

of the casing, said pane having a flat or plane portion covering one of said compartments and abutting against said partition and having on such flat or plane portion a warning signal on one side of the partition 15 and on the opposite side a lens for a tail light, and a bulb for each compartment.

In testimony whereof, I hereunto affix my signature.

NORMAN FLLIOTT.
